PARABOLIC REFLECTOR

Samuel J. Mason, Boston, Mass., assignor, by
mesne assignments, to the United States of
America as represented by the Secretary of the
Navy

Application September 14, 1945, Serial No. 616,410

6 Claims. (Cl. 250—33.63)

1

This invention relates to directional microwave antennas having a paraboloid reflector, and particularly to paraboloid reflectors having a periphery so shaped as to obtain maximum gain and minimum side lobes for a given reflector aperture area and a given feed pattern.

For many purposes in connection with radio echo systems, it is desired that the antenna gain be very high in order to obtain a high degree of directivity of the radiated beam; and to avoid useless dissipation of radiated energy and spurious directivity interpretations, it is desirable that the side lobes of the radiation beam pattern be minimized.

For the gain of a paraboloid antenna to be high, the phase of radiation across the aperture should be constant. This implies that the wave front impinging on the paraboloid should be as nearly spherical as possible. The center of this diverging spherical wave front called the electrical center of the feed is the point located at the focus of the paraboloid.

The size of side lobes is affected by the phase and intensity of illumination at the periphery of the reflector. It is the object of this invention to provide an antenna having a reflector whose periphery is shaped to produce maximum gain and minimum side lobes for a given area of paraboloid. Another object is to construct a paraboloid reflector having maximum efficiency for a given aperture area.

This invention results from the discovery that if the periphery of the paraboloid reflector is shaped to follow a line of constant illumination intensity or, as it may be called, an illumination contour line, there results a maximum of gain and minimum of side lobe radiation for a given reflector area. With a primary feed possessing a known radiation pattern placed at a known point near the focus of the paraboloid, and making a known angle with the axis of the paraboloid, the distribution of radiation intensity over the surface of the paraboloid can be calculated. The distribution of energy over a sphere centered on the feed, and of radius "f" is taken to be the focal length of the paraboloid, is first studied in any of several possible coordinate systems, and then the intensity distribution on the paraboloid surface may be calculated by attenuating the distribution on the sphere by the factor $(f/r)^2$ where "r" is the radius vector from the focus to the paraboloid surface. Since there is no divergence of the radiation from the paraboloid surface to the paraboloid aperture, the intensity distribution in the aperture is also determined. In order that the paraboloid radia-

tion beam pattern may have low side lobes the periphery of the paraboloid should follow some one of the lower intensity contours of aperture illumination.

- 5 Other methods may be followed for ascertaining the location of the contour lines on any given paraboloid of revolution with a particular feed located at a known position and attitude relative to the reflector, for example, by direct measurement. The essence of this invention is that by using a portion of such paraboloid cut along one of the lower intensity illumination contour lines the desirable consequences of high gain and low side lobes will result.
- 15 Fig. 1 is a section diagram of a horn feed and a spherical surface and a paraboloid surface for illustrating the explanation of calculation of constant illumination contour lines on the paraboloid;
- 20 Fig. 2 is a graph of constant illumination contour lines;
- 25 Fig. 3 is a perspective diagram showing contour lines on a paraboloid; and
- Fig. 4 is a perspective view of a paraboloid with a periphery shaped to conform to a contour line, together with a feed for illuminating the reflector.
- 30 Referring now to Fig. 1, there is represented a feed horn 5 (having in itself a directional characteristic pattern, not shown) positioned at the focus 7 of a paraboloid reflector 9 of focal length "f," and inclined at an angle to the axis of the paraboloid 9. As a result of the feed pattern there will be a variation in the intensity of illumination of the reflector at different points, for example, 11, 12, 13, 14, 15 (in one vertical plane) corresponding to points 21, 22, 23, 24, 25 respectively on a sphere centered at the paraboloid focus 7 and having its radius equal to the focal length "f." The magnitudes of intensity at points 21, 22, 23, 24 and 25 will be the equivalent of the feed pattern. To calculate therefrom the intensities at the corresponding points on the paraboloid surface, it is necessary because of the 35 divergence of the energy to attenuate by a factor of $(f/r)^2$, where r is a parameter representing the distance from focus to each particular point on the paraboloid surface. Since there is no divergence of the radiation from the paraboloid surface to the paraboloid aperture, the intensity on the aperture for corresponding points 31, 32, 33, 34, 35 is also determined thereby. By joining up points of equal intensity, lines of constant 40 intensity of illumination or illumination contour 45 lines are obtained as shown in Fig. 2.
- Fig. 2 is a typical set of illumination contour

lines showing a half pattern, and in this instance, the periphery of the paraboloid reflector shown in Fig. 4 was shaped to coincide substantially with the -14 db illumination line 40 the only deviation being to round off the end, as shown by dotted line 42, for practical reasons.

Fig. 3 shows as a perspective sketch a paraboloid reflector 50 bearing on its surface a family of equal illumination contour lines 51, 52, 53, 54, and 55, which result from a certain wave guide feed 56. If the paraboloid be shaped to conform to any one of these lines as for example line 54, the resulting reflector will have maximum area efficiency in the sense of highest gain and lowest side lobes for the area of reflector.

Fig. 4 shows an embodiment of the principle of this invention and includes a paraboloid reflector 60 with periphery 61 shaped in accordance with the above to conform to a contour line of constant illumination intensity. Also shown is the wave guide feed 63 for the same, inclined at an angle with the paraboloid axis so that the result is a nonsymmetrical reflector shape with reference to the paraboloid axis.

While a specific embodiment and application of the invention has been shown, the principle of the invention is entirely general, and therefore the invention should not be deemed limited to the particular embodiment shown.

What is claimed is:

1. A directional microwave antenna system comprising a reflector disposed entirely in the surface of a theoretical paraboloid, a feed for radiating electromagnetic wave energy in a predetermined pattern at a particular frequency, said predetermined radiation pattern being nonsymmetrical with respect to the axis of said paraboloid, said reflector having a periphery coincident with a constant intensity of illumination contour line of said predetermined radiation pattern of said feed.

2. An antenna system comprising, a reflector and a feed for radiating electromagnetic wave energy in the direction of said reflector in a predetermined radiation pattern at a particular frequency, said predetermined radiation pattern being nonsymmetrical with respect to the axis of said reflector, the periphery of said reflector being defined as the intersection in the surface of said reflector of a constant intensity of illumination contour line of said predetermined radiation pattern of said feed.

3. A directional microwave antenna system comprising a reflector in the form of a portion of a paraboloid of revolution and a feed disposed along the axis of said paraboloid for radiating electromagnetic wave energy toward said reflector along said axis in a predetermined radiation pattern at a particular frequency, said predetermined radiation pattern being nonsymmetrical

with respect to said axis, said reflector having a periphery coincident with a contour line of constant illumination intensity of said predetermined radiation pattern of said feed.

5. An antenna comprising a reflector having an axis of directivity, a feed for radiating electromagnetic wave energy in a predetermined pattern at a particular frequency, said feed being positioned so as to illuminate said reflector, said radiation pattern being other than a solid of revolution about the axis of directivity of said reflector, said reflector having a periphery coincident with a preselected constant intensity of illumination contour line of said radiation pattern at said particular frequency.

10 6. An antenna comprising a reflector having an axis of directivity, a feed for radiating electromagnetic wave energy in a predetermined pattern at a particular frequency, said radiation pattern having a major axis of directivity, said feed being positioned so as to illuminate said reflector with said major axis of directivity of said feed at an angle to the axis of directivity of said reflector, said reflector having a periphery coincident with a preselected constant intensity of illumination contour line of said radiation pattern at said particular frequency.

20 7. An antenna system comprising a reflector having a paraboloidal reflecting surface with an axis of directivity and a focus disposed along said axis, a feed positioned at said focus for radiating electromagnetic wave energy in a predetermined pattern at a particular frequency, said radiation pattern having a major axis of directivity, said feed being oriented so as to illuminate said reflector with said major axis of directivity of said feed at an angle to said axis of directivity of said paraboloidal reflecting surface, said paraboloidal reflecting surface having a periphery coincident with a preselected constant intensity of illumination contour line of said radiation pattern at said particular frequency.
